Primary Examiner — Cynthia Underwood(74) *Attorney, Agent, or Firm* — Winston & Strawn LLP(57) **CLAIM**

The ornamental design for an air hose handling device, as shown and described.

DESCRIPTION

FIG. 1 is a perspective view of the new design for a first embodiment of an air hose handling device; FIG. 2 is a front view of the device of FIG. 1; FIG. 3 is a top view of the device of FIG. 1; FIG. 4 is a side view of the device of FIG. 1; and, FIG. 5 is a bottom view of the device of FIG. 1. The broken away symbols in the air hose handling device indicate that any portion of the article beyond what is shown forms no part of the claim.
